CLAIM

I claim the ornamental design for a compartmentalized container, as shown and described.

DESCRIPTION

FIG. 1 is a perspective view of a compartmentalized container showing inventor's new design;

FIG. 2 is a top plan view thereof;

FIG. 3 is a top plan view of FIG. 2;

FIG. 4 is a bottom plan view of FIG. 2;

FIG. 5 is a left side view of FIG. 2;

FIG. 6 is a right side view of FIG. 2;

FIG. 7 is bottom plan view of FIG. 1;

FIG. 8 is a sectional view of said compartmentalized container as indicated in FIG. 2; and,

FIG. 9 is a sectional view of said compartmentalized container as indicated in FIG. 2.
